UNITED STATES PATENT OFFICE.

FRANK J. McGOWAN, OF MECHANICSVILLE, NEW YORK.

AUTOMOBILE WASHER.

1,418,383.

Specification of Letters Patent. Patented June 6, 1922.

Application filed October 7, 1920. Serial No. 415,334.

To all whom it may concern:

Be it known that I, FRANK J. McGOWAN, a citizen of the United States, residing at Mechanicsville, in the county of Saratoga 5 and State of New York, have invented certain new and useful Improvements in Automobile Washers, of which the following is a specification, reference being had therein to the accompanying drawing.

10 My invention relates to new and useful improvements in washing and scrubbing devices, and more particularly to an automobile washer.

The principal object of the invention is 15 the provision of a device of this character of the fountain type wherein a stream of water may be continuously discharged through the brush or sponge connected to the head.

20 A further object resides in the provision of means whereby the flow of water may be cut off at will and novel means for detachably connecting the brush or sponge to the head.

25 With the above and other objects in view which will appear as the description proceeds, my invention consists in the novel details of construction and arrangement of parts which will be clearly understood from 30 the following specification and drawings, and while I have illustrated and described the preferred embodiment of the invention, it will be understood that such changes may be made in the construction and arrangement of parts as will fall within the scope 35 of the appended claims.

In the drawings:

Figure 1 is a side elevation.

Figure 2 is a top plan.

40 Figure 3 is a transverse vertical section on the line 3—3 of Fig. 2.

Figure 4 is a longitudinal vertical section on the line 4—4 of Fig. 2.

In carrying out my invention, I provide a 45 head 1 having a flange 2 extending outwardly from one face, the inner face of the flange being tapered as shown at 3 and the flange forming a recess adapted to receive a portion of a sponge 4 which will be secured to 50 the head in a manner to be later described.

A passage 5 extends from one edge of the head to a point adjacent the center and has a right-angle extension 6 communicating with the recess formed by the flange 2. The 55 passage 5, adjacent the outer periphery of the head, is threaded to receive the threaded end

of a pipe 7 which is secured at the opposite end to a hose 8 which may be connected to any suitable source of water supply. The hose will be secured to the pipe by suitable 60 clamping bands 9 and the pipe may be used as a handle when using the device. A valve 10 is provided in the pipe 7, intermediate its ends and while I have illustrated the valve of the rotary type, it will be understood that 65 any other suitable form of valve might equally as well be used. In the form of valve illustrated a suitable finger hold 12 is provided for turning.

The face of the head, opposite to that having the flange 2, is provided with a recess 13 and holes 14 are formed through the head and communicate with the recess 13 and the recess formed by the flange 2. A circular plate 15 is rotatably mounted in the recess 70 13 by a screw or other suitable fastening 16 and has oppositely disposed notches 17 formed in its edge, said notches adapted, when the plate is properly turned, to register with the openings 14 and the upwardly extending flange 18 is formed around the upper edge of the plate and is interrupted at the notches 17, as clearly shown. The flange 18, on one side of each notch, is beveled as 75 shown at 19 for a purpose to be later described. The upwardly extending flange 20 is formed centrally of the plate 15 and surrounds the screw or other fastening member 16. This flange 20 will preferably be roughened so that it may be used as a finger hold 80 85 for turning the plate when desired.

For securing the sponge 4 to the head I have provided a U-shaped bolt 21 having notches 22 adjacent the ends of the arms. The horizontal portion of the U-shaped bolt 95 will extend through the sponge and the arms will be passed through the openings 14 in the head 1. In passing the arms through the openings 14 the plate 15 will have to be turned so that the notches 17 therein register 100 with the openings. After the arms are passed through the openings and notches the plate 15 will be rotated by taking hold of the flange 20 and the flange 18 on the outer edge of the plate will engage in the notches 22. The 105 beveled portions 19, of the flange 18, will draw the arms through the openings and draw the sponge 4 into the recess in the head 1 formed by the flange 2. The inclined end wall 3 of the flange will cause the sponge to 110 be tightly gripped and pressed in the recess. When it is desired to remove the sponge the

plate may be further rotated to bring the notches 17 in alinement with the openings 14.

From the above detailed description it is thought that the advantages and manner of using the washer will be clearly understood. While primarily intended for washing automobiles, it will be understood that it might equally as well be used for a number of other purposes, and while I have specified a sponge as being used in connection with the head, it will be understood that a brush of various types might be used or a chamois or other suitable cloth might be used. A continuous stream of water is applied to the head and may be cut off when desired by operating the valve. Should the sponge become worn, or it is desired to remove and replace for any other purpose, it may be easily and quickly disconnected from the head. The beveled construction of the flange 18 around the outer edge of the plate 15 draws the sponge tightly into the recess formed in the head by the flange 2. The recess 13 on the opposite face of the head receives the rotatable plate and fastening means below the face of the head so that there will be no projections beyond the face of the head which might mar the automobile or other surfaces upon which the device is being used. If a supply of running water is not available my washing device might be used by merely inserting the sponge and head in a bucket or similar receptacle for containing water and then apply to the surface being washed. The head 1 may be made of wood or other suitable material.

Having fully described my invention, what I claim as new and desire to secure by Letters Patent is:

1. A device of the character described comprising a head, a U-bolt extending through

the head and provided with notches, a plate rotatable connected to the head and adapted to engage in the notches of the U-bolt, and a sponge carried by the U-bolt.

2. A device of the character described comprising a head having recesses in opposite faces, a U-bolt extending through the head and having notches therein, a plate rotatably connected to the head within the recess in one face and adapted to engage the recesses in the U-bolt, and a sponge carried by the U-bolt and adapted to be drawn into the recess in the opposite face of the head.

3. A device of the character described comprising a head, a U-bolt extending through the head and having notches therein, a rotatable plate connected to the head and having oppositely disposed notches to receive the arms of the U-bolt, an upwardly extending flange formed on the plate between the notches therein and adapted to be received in the notches of the U-bolt, said flange being beveled at one side of each notch, and a sponge carried by the U-bolt.

4. A device of the character described comprising a head having recesses in opposite sides thereof, a sponge having a portion thereof received in one of the recesses, a member engaging the sponge and adapted to pass through the head and extend into the recess in the opposite face, and means wholly within the said last mentioned recess adapted to engage the sponge member to secure the sponge to the head.

In testimony whereof I hereunto affix my signature in the presence of two witnesses.

FRANK J. McGOWAN.
